METALWORKING MACHINE

Homer G. Kellogg, Detroit, Mich., assignor to
 Motor Products Corporation, Detroit, Mich., a
 corporation of New York

Application May 13, 1935, Serial No. 21,289

12 Claims. (Cl. 153—3)

This invention relates generally to rolling machines and refers more particularly to apparatus for forming strip stock into an arcuate section of predetermined cross sectional contour. 5 One of the principal objects of this invention resides in the provision of apparatus having means for bending a strip of stock to a predetermined arcuate configuration, and having means to prevent buckling of the strip during the bending operation.

Another advantageous feature of this invention resides in the provision of a rolling machine having means for bending a strip of stock to a predetermined arcuate configuration subsequent to rolling the strip to the desired cross sectional contour, and having means for exerting a lateral pressure upon a portion of the strip during the bending operation to prevent buckling of this portion. 20 An additional object of the present invention consists in the provision of a rolling machine having a fixture at the delivery end thereof periodically operable to bend the strip to a predetermined arcuate configuration, and having means cooperating with certain of the forming rolls, during the bending operation of the fixture, to exert a lateral pressure upon the portion of the strip therebetween.

A further advantageous feature of the present 30 invention resides in the novel means provided for actuating the bending fixture and pressure applying means in timed relation to each other. The aforesaid means, as well as the above objects and other advantageous features of the 35 present invention, will be made more apparent as this description proceeds, especially when considered in connection with the accompanying drawings, wherein:

Figure 1 is a semi-diagrammatic side elevational view of a portion of a rolling machine equipped with the present invention;

Figure 2 is a fragmentary perspective view of a portion of the machine shown in Figure 1;

Figure 3 is a sectional view taken substantially on the plane indicated by the line 3—3 of Figure 1;

Figures 4, 5, and 6 are respectively cross sectional views taken substantially on the lines 4—4, 5—5 and 6—6 of Figure 3;

Figure 7 is a detailed perspective view of a part of the lateral pressure applying means;

Figure 8 is a similar view of a cooperating part of the aforesaid means; and

Figure 9 is a cross-sectional view through a molding strip, illustrating one type of construct-

tion capable of being formed by the present machine.

Referring now more in detail to the drawings, it will be noted that there is diagrammatically illustrated in Figure 1, a portion of a rolling machine 10 comprising a plurality of sets of forming rolls 11 cooperating with each other to form a strip of flat stock to a predetermined cross-sectional contour. For the purpose of illustration, the rolls 11 may be considered to possess the configuration required to form the strip to the cross-sectional contour illustrated in Figure 9, although it is to be understood that this contour may vary materially without departing from the spirit and scope of this invention.

In detail, the strip is designated generally in Figure 9, by the reference character 12 and comprises a transversely curved wall 13 provided at one edge with a return-bent portion 14 terminating in an inwardly extending flange 15. 20 The opposite longitudinal edge of the strip is provided with a flange 16 extending in the same direction from the wall 13 as the return-bent portion 14 and terminating in a flange 17 projecting toward the flange 15 previously set forth. 25

The strip 12 is formed in the rolling machine 10 with the return-bent portion 14 extending downwardly from the wall 13 and provision is made, beyond the delivery end of the machine, in the form of a fixture 18 for bending the strip upwardly about the periphery of a forming roll 19 constituting the top roll of the end set of forming rolls 11. As shown particularly in Figure 2, the forming roll 19 has a portion 20 corresponding in transverse contour to the cross sectional contour of the top wall 13 of the strip, and is provided with another portion 21 engageable with the periphery of a flange 22 extending radially outwardly from the cooperating forming roll 23. Upon reference to Figure 3, it will 40 be noted that the front face 24 of the radial flange 22 forms a continuation of the portion 20 of the forming roll 19 and conforms in shape to the contour of the downwardly extending return-bent portion 14 of the strip.

It will also be observed from Figure 3, that the forming roll 23 is secured to a drive shaft 25, while the cooperating forming roll 19 is secured to a shaft 26 driven from the shaft 25, through the medium of suitable gearing 27. The 50 axis of rotation of the forming roll 19 is substantially parallel to the axis of rotation of the cooperating forming roll 23, and both of these axes are arranged in a common vertical plane.

Upon referring again to Figure 3, it will be 55

noted that the forming roll 23 forms the second roll of the end set 11 and that this roll not only cooperates with the roll 19 in the manner previously stated, but also cooperates with a third forming roll designated generally by the reference character 28. The forming roll 23 is secured to a shaft 29 journaled for rotation about an axis extending perpendicular to the axis of the rolls 19 and 23, but located in a common plane with the latter axes. In detail, the upper end of the shaft 29 is journaled in a block 29' slidably supported in a wear plate 30 for shifting movement in the direction of the axes of rotation of the aforesaid forming rolls, and the lower end of the shaft 29 is journaled in a collar 31 mounted for axial sliding movement upon the drive shaft 25 at the front side of the forming roll 23. Thus it will be seen that the forming roll 28 is mounted for rotation at the front side of the forming roll 23 and, in the present instance, is provided with a peripheral portion 32 cooperating with the surface 24 of the roll 23 to receive the return-bent portion 14 of the strip therebetween.

25 Referring again to Figure 3, it will be noted that the forming roll 28 is driven from the forming roll 23, notwithstanding the fact that the former is shiftable relative to the latter. In detail, the front side of the forming roll 23 is fashioned to form, in effect, a beveled gear 33 adapted to mesh with a correspondingly beveled gear 34 formed on the forming roll 28. The co-operating teeth of the two beveled gear portions are fashioned to provide a limited displacement 35 of the roll 28 relative to the roll 23 without destroying the driving connection therebetween.

It has previously been stated that as the strip is delivered from between the end set of forming rolls 11, the same is periodically bent upwardly 40 about the portion 20 of the roll 19, by means of the fixture 18. In the present instance, the fixture 18 comprises an arm 35 having the end 36 journaled on the drive shaft 25 at the rear side of the forming roll 23 and having a follower 37 at the free end thereof engaging a cam 38. The cam 38 is secured to a shaft 39 driven through the medium of reduction gearing 40 from the drive shaft 25, and is provided with a cam surface 41 of a contour varying in dependence upon 45 the degree of curvature desired and the number of bends to be formed in the strip. The actual bending of the strip is effected by means of a plate 42 secured to the arm 35 intermediate the ends and grooved as at 43 to provide clearance 50 for the return-bent portion 14 of the strip, with the result that the actual bending pressure is exerted upon the flanges 16 and 17 of the strip.

With the foregoing arrangement, it will be apparent that the strip is bent upwardly about 60 the portion 20 of the roll 19 upon actuation of the fixture 18 by the cam 38, and it will also be observed that during the bending operation the return-bent portion 14 stretches to some extent. This stretching of the return-bent portion 14 of 65 the strip has a tendency to deform the same, and in order to prevent deformation, pressure is applied to the return-bent portion during the bending operation. In general, the above is accomplished by moving the roll 28 in a direction toward the cooperating roll 23, during the bending operation, to effectively grip the return-bent portion 14 of the strip between the surfaces 24 and 32 of the rolls. In detail, the roll 28 is positively shifted toward the roll 23, by means of an 70 arm 44 having an integral collar 45 at one end

journaled upon the drive shaft 25 at the front side of the collar 31 and having a cam face 46 cooperating with a cam face 47 on the collar 31 to move the latter toward the roll 23 when the free end of the arm 44 is moved upwardly. Inasmuch as the forming roll 28 is mounted on the collar 31, it necessarily follows that the portion 28 of this roll will be moved toward the surface 24 of the roll 23 when the collar 31 is urged axially of the shaft 25 toward the roll 23 by the 10 arm 44.

The required upward displacement of the arm 44 to effect the foregoing results is accomplished by means of a cam 49 secured to the shaft 39 adjacent the cam 38 and having a cam surface 15 50 predetermined in dependence upon the configuration of the cam surface 41, so as to apply the desired pressure to the return-bent portion 14 of the strip through the forming roll 28, during the operation of the fixture 18 by the cam 20 38 to bend the strip. This arrangement insures maintaining the desired contour of the return-bent portion 14 during the bending operation and, in this connection, it may be pointed out that the shape of the remaining portion of the 25 strip is maintained during the bending operation, by means of an articulated shoe 51 engageable within the strip in the manner shown in Figure 4.

Referring now, generally, to the operation 30 of the bending fixture 18 and pressure applying means, it will be noted that as the follower on the free end of the arm 35 rides upon the cam surface 41 of the cam 38, the plate 42 engages the inwardly directed flanges on the strip and bends the latter about the peripheral portion 20 of the forming roll 19 to a curvature depending upon the configuration of the cam surface 41. At substantially the same time, the free end of the arm 44 is moved upwardly by the cam surface 50 40 on the cam 49 and this upward movement of the free end of the arm 44 causes the collar 45 to rock about the shaft 25 in a direction to urge the collar 31 toward the forming roll 23 through the medium of the cooperating 45 engaging cam faces 46 and 47. Inasmuch as the forming roll 28 is carried by the collar 31, it necessarily follows that the portion 32 of the forming roll 28 is urged toward the surface 24 50 of the forming roll 23 to clamp the return-bent portion of the strip therebetween. It being understood that sufficient play is provided between the cooperating engaging beveled teeth 33 and 34 to provide for the required relative movement of the two aforesaid rolls. It will also be understood that the cam surface 50 is designed to maintain the pressure on the return-bent portion 14 of the strip throughout the entire bending 55 operation.

Thus from the foregoing, it will be observed 60 that I have provided relatively simple means for bending strips of irregular cross sectional contour without deforming or otherwise interfering with the desired shape of the strip. It will also be apparent that the means for accomplishing 65 the above results operates automatically and is not restricted to any one particular shape of strip.

What I claim as my invention is:

1. In a machine for bending a strip of stock having a body portion and having a portion extending at an angle to the body portion, means for advancing the stock in the direction of its length along a predetermined path of travel, a fixture mounted for oscillation about an axis extending transversely to the path of travel and 75

engageable with the stock to bend the latter, and cooperating means on opposite sides of the angularly extending portion of the stock for gripping the angularly extending portion of the stock therebetween during the operation of the fixture to bend the stock.

2. In a machine for bending a strip of stock having a body portion and having a portion extending at an angle to the body portion, means for advancing the stock in the direction of its length along a predetermined path of travel, a fixture mounted for oscillation about an axis extending transversely to the path of travel and engageable with the stock to bend the latter, means for periodically moving the fixture into engagement with the stock, and means effective during the intervals the fixture is moved into engagement with the stock to exert a clamping pressure on opposite sides of the angularly extending portion of the strip in the region the latter is bent.

3. In a machine for bending a strip of stock having a body portion and having a portion extending at an angle to the body portion, means for advancing the stock in the direction of its length along a predetermined path of travel, a fixture mounted for oscillation about an axis extending transversely to the path of travel and engageable with the stock to bend the latter, cam means for periodically moving the fixture into engagement with the strip, and cam means operating during the interval of operation of the aforesaid cam means to move the fixture into engagement with the strip to exert a lateral pressure upon the angularly extending portion of the strip.

4. In a machine for bending a strip of stock having a body portion and having a portion extending at an angle to the body portion, a revoluble roll having a portion engaging one side of the angularly extending portion of the strip, a cooperating revoluble roll having a portion engaging the opposite side of the angularly extending portion, means engageable with the strip as it passes from between the rolls to bend the strip to the desired arcuate contour, and means for relatively moving the rolls toward each other during the bending operation to grip the angularly extending portion therebetween.

5. In a machine for bending a strip of stock having a body portion and having a portion extending at an angle to the body portion, a driven roll having a portion engageable with one side of the angularly extending portion of the strip, a second roll mounted for rotation about an axis extending at substantially right angles to the axis of the driven roll and having a portion engageable with the opposite side of the angularly extending portion, means positioned beyond the rolls for engaging the strip to bend the same to the desired arcuate contour, and means for relatively moving the rolls toward each other during the bending operation to clamp the angularly extending portion therebetween.

6. In a machine for bending a strip of stock having a body portion and having a portion extending at an angle to the body portion, means for advancing the stock in the direction of its length along a predetermined path of travel including a revoluble roll having a portion engageable with one side of the angularly extending portion of the strip, a second roll driven by the first roll and rotatable in a plane perpendicular to the plane of rotation of the first roll and having a portion engageable with the

opposite side of the angularly extending portion, means positioned beyond the rolls for engaging the strip to bend the same to the desired arcuate contour, and means for relatively moving the rolls toward each other during the bending operation to clamp the angularly extending portion therebetween.

7. In a machine for bending a strip of stock having a body portion and having a portion extending at an angle to the body portion, a revoluble roll having a portion engaging one side of the angularly extending portion of the strip, a cooperating revoluble roll having a portion engaging the opposite side of the angularly extending portion, a third roll engageable with the body of the strip, means located beyond the rolls and movable into engagement with the strip to bend the latter about the third roll, and means for relatively moving the first and second rolls toward each other during the bending operation to grip the angularly extending portion of the strip therebetween.

8. In a machine for bending a strip of stock having a body portion and having a portion extending at an angle to the body portion, a revoluble roll having a portion engaging one side of the angularly extending portion of the strip, a cooperating revoluble roll having a portion engaging the opposite side of the angularly extending portion, a third revoluble roll engageable with the body of the strip and with the periphery of the first roll, a fixture mounted for oscillation about an axis parallel to the axis of the first roll and engageable with the strip beyond the rolls to bend the stock about the third roll, means for periodically moving the fixture into engagement with the strip, and means for relatively moving the first and second rolls toward each other during the bending operation to grip the angularly extending portion of the strip therebetween.

9. In a machine for bending a strip of stock having a body portion and having a portion extending at an angle to the body portion, means for advancing the stock in the direction of its length along a predetermined path of travel including a revoluble roll having a portion engageable with one side of the angularly extending portion of the strip, a second roll driven by the first roll for rotation in a plane perpendicular to the plane of rotation of the first roll and having a portion engageable with the opposite side of the angularly extending portion, a third roll rotatable about an axis parallel to the axis of the first roll and disposed in the plane of the latter axis, said third roll having a portion engageable with the body of the strip, a fixture mounted for oscillation about the axis of the first roll and engageable with the strip to bend the stock about the third roll, cam means for periodically oscillating the fixture, and means for relatively moving the first and second rolls toward each other during the bending operation to grip the angularly extending portion of the strip therebetween.

10. In a machine for bending a strip of stock having a body portion and having a portion extending at an angle to the body portion, means for advancing the stock along a predetermined path of travel, means for periodically exerting a lateral pressure upon the angularly extending portion of the strip of stock as it is advanced along said path of travel, and means operating during the interval of operation of the aforesaid means to bend the strip of stock to a predetermined arcuate contour.

11. In a machine for bending a strip of stock

having a body portion and having a portion extending at an angle to the body portion, means for advancing the stock along a predetermined path of travel, means engageable with the strip of stock as it is advanced along said path of travel to bend the strip to a predetermined contour, members positioned upon opposite sides of the angularly extending portion of the strip of stock in the region at which bending of the strip occurs, and means for relatively moving the members toward each other in timed relation to the operation of the bending means to grip the angularly extending portion therebetween.

12. In a machine for bending a strip of stock having a body portion and having a portion extending at an angle to the body portion, means for advancing the stock along a predetermined path of travel, means positioned upon opposite sides of the angularly extending portion of the stock and cooperating to exert a clamping pressure against the angularly extending portion as the stock is advanced along said path of travel, and means operating during the interval of operation of the aforesaid means to bend the strip of stock out of said path of travel. 5

HOMER G. KELLOGG.
